UNITED STATES PATENT OFFICE.

JOHN E. GREENAWALT, OF DENVER, COLORADO.

BLOWER.

1,261,806.

Specification of Letters Patent. Patented Apr. 9, 1918.

Application filed May 12, 1915, Serial No. 27,574. Renewed August 29, 1917. Serial No. 188,871.

To all whom it may concern:

Be it known that I, JOHN E. GREENAWALT, a citizen of the United States, residing at Denver, in the county of Denver and State 5 of Colorado, have invented certain new and useful Improvements in Blowers, of which the following is a full, clear, and exact description, reference being had to the accompanying drawings, forming a part hereof.

10 My invention has relation to improvements in turbine blowers, and it consists in the novel features of construction more fully set forth in the specification and pointed out in the claims.

15 The present invention is directed to turbine compressors, blowers or pumps of the centrifugal type for compressing or moving fluids such as air and gases, the special object sought being the conversion of the velocity 20 energy of such fluid into pressure by means operating to discharge the rapidly moving fluid from the impeller into the collecting or receiving scroll of the compressor without the formation of eddies or the production of 25 shocks to the currents of the fluid in motion. As well understood in the art, the fluid as it leaves the impeller of a centrifugal machine, is under the influence of two sources 30 of energy, to wit, (a) the centrifugal force acquired by the fluid in its movement along the impeller blades, and (b) the kinetic energy contained in the fluid due to its velocity upon leaving the periphery of the impeller. The efficiency of such a machine is 35 in a large measure dependent on the extent of conversion of this kinetic or velocity energy into potential energy in the form of static pressure; and in the present embodiment of my invention special means are pro- 40 vided to effect the necessary conversion of said velocity energy into a pressure head, such means taking the form of ducts or channels which remove the fluid from the influence of the impeller, and conduct the same 45 into the receiving or collecting scroll without shock or loss of energy caused by re-acting eddies in the fluid discharged from the impeller wheel, the ducts or channels being so disposed as to cause an even diffusion of the 50 fluid by a lateral movement thereof after leaving the impeller, the fluid being finally discharged from the sides of the diffusion member on which the ducts are formed, into the receiving scroll. In the diffusion ap- 55 paratus of centrifugal machines as hereto-

fore constructed, the diffusion vanes are disposed around the periphery of the impeller with their receiving ends supposedly tangent to the outlet velocity of the fluid, the vanes discharging the fluid into the receiving scroll which is in turn connected with the eduction pipe. In practice however, only a small percentage of the fluid particles are projected from the impeller in a true tangential direction and the consequence is that the mass of the fluid strikes the vanes with considerable impact thus resulting in considerable reduction of efficiency. In my improvement the diffusion vanes (or their equivalents) are disposed at 70 a comparatively slight angle to the direction of flow of the fluid while under the influence of the impeller, said vanes forming spiral channels or conduits which receive the fluid immediately as it leaves the impeller, and guide and turn it in a gradual and definite manner laterally into the collecting scroll without material impact or shock, or the formation of re-acting eddies, so that the full momentum and velocity of 75 the rapidly moving fluid is availed of and utilized in the production of pressure in the collecting scroll. The advantages of the invention will be fully apparent from a detailed description of one form of apparatus 80 which may be utilized to accomplish the objects sought, and which is illustrated in the accompanying drawings in which—

Figure 1 is a combined side elevation and middle vertical longitudinal section of a 90 blower to which my invention is applied; Fig. 2 is an end elevation of the blower; Fig. 3 is an enlarged vertical middle transverse section, parts being left in elevation; Fig. 4 is a side view of the annular diffusion member or ring detached; Fig. 5 is a transverse section through the diffusion ring on the line 5—5 of Fig. 4; Fig. 6 is a sectional detail on the line 6—6 of Fig. 3, with parts broken away; Fig. 7 is a face elevation of one of the 95 impeller blades with securing disk in section on the line 7—7 of Fig. 8; Fig. 8 is an elevational view at right angles to Fig. 7, the impeller shaft being in section; and Fig. 9 is a diagrammatic plan showing a modified form 100 of diffusion ring.

Referring to the drawings, and for the present to Figs. 1 to 8 inclusive, C represents a conventional blower casing having opposing, conical, machined side walls *w*, 110

w, spaced apart, between which rotates at a high speed an impeller composed of a series of radial blades *B*, the same being keyed or otherwise secured to the impeller shaft *S* disposed transversely to said walls. The shaft *S* is mounted in bearings *D*, *D*, one end thereof being provided with a coupling member *P* which is secured to a corresponding member *P'* of any motor or power shaft *S'* for imparting rotation to the impeller. The casing is provided with induction or intake openings *O*, *O'*, and with the usual eduction leg *E* as well understood in the art.

15 In the present embodiment of my invention, the walls *w*, *w*, are provided with laterally and outwardly extending annular offsets or shoulders *s*, *s*, at points opposite the tips of the impeller blades, said shoulders forming the inner walls of the collecting (or receiving scroll 1, the parts referred to being cast integrally in two sections which are subsequently assembled and fastened together through the flanges *h*, *h*. The inner faces of the offsets *s*, *s*, are disposed on a common cylindrical surface lying close but exterior to, the circle defined by the tips of the impeller blades (Fig. 3) said offsets forming supporting ledges for the annular diffusion member or ring 2, embracing and snugly fitting, the cylindrical surface aforesaid. The diffusion member or ring 2 may be said to be interposed between the impeller and the collecting scroll 1, the collecting chamber of the scroll being the space between the scroll walls and said ring 2, the latter serving (as presently will more fully appear) to properly diffuse the fluid as it leaves the impeller, and conduct the same into the scroll-chamber. Disposed on the inner face of the ring 2 on each side of a medial line *z* thereof, are a series of ribs or vanes 3, said ribs being inclined at a slight angle to said medial line and extending therefrom to the side edges of the ring. Preferably, a rib or vane on one side converges to a common vertex with a rib or vane on the opposite side, thereby forming corresponding series of laterally diverging channels *a* between the ribs, the converging termini of the channels being disposed along the medial line *z* of the ring (Fig. 5). The width of the ring 2 is considerably in excess of the distance or gap between the side walls of the casing *C* at the tips of the impeller blades (Fig. 3), the ring when in position not only spanning said gap, but extending some distance over the ledges or shoulders *s*, *s*, above referred to, it being understood that the ring is disposed symmetrically about the central plane of rotation of the impeller blades. The inside diameter of the diffusion ring is such that when inserted into position (the same being preferably made in two halves for ready assem-

bling), the free edges of the ribs 3 will, for considerable portions of their lengths rest on the inner faces of the shoulders *s*, thereby closing the otherwise open peripheries of the channels *a* and converting the latter into tubular ducts, conduits or nozzles through which the air as it leaves the impeller is caused to travel before the same is discharged into the scroll chamber (Figs. 3, 6). These nozzles or conduits being disposed on the surface of a cylinder and inclined to the axis thereof will naturally partake of the form of a spiral, to traverse which, the air currents entering the same from the impeller blades must travel a suitable distance circumferentially (of the ring 2 and the ledges *s*) and at the same time laterally, the air being finally discharged into the chamber of the collecting scroll 1 at points between the sides of the ring 2 and the adjacent walls of the scroll. In a blower having an impeller four feet in diameter, the circumferential travel of the air through the nozzles *a* would be in the neighborhood of thirty-five inches, the lateral travel or deflection thereof by reason of the slight inclination of the nozzles, being only about four and one-half inches before passing into the scroll chamber. With the diffusion ring 2 disposed symmetrically about the central plane of rotation of the impeller, the inner ends of the diverging channels *a* will terminate at said plane, and be in proper position to receive the fluid the instant it leaves the impeller blades. Thereafter the channels or nozzles will guide the fluid circumferentially, and gradually and definitely turn the same laterally and finally discharge the fluid into the scroll chamber without any material shock or impact, and without the formation of re-acting eddies. By the employment of the diffusion channels or nozzles as here described, the full momentum and velocity of the rapidly moving fluid as it leaves the impeller is utilized in the production of pressure in the chamber of the collecting scroll, the diffusion of the fluid being brought about without material disturbance of the continuity of flow, velocity, or direction which the fluid as it leaves the impeller should possess to bring about a high efficiency in this type of apparatus.

The apparatus here shown is specially adapted for use with air or gases, that is to say, with elastic fluids, and obviously may be operated as a compressor or as an exhauster for producing a partial vacuum; and while the apparatus illustrated is eminently adapted for the purpose here in view, I may depart therefrom in many particulars without a departure from the nature or spirit of my invention. As an instance of such departure, the diffusing ribs or vanes need not meet at a common vertex as shown in the first form described but may be stag-

gered as shown diagrammatically in Fig. 9 where the diffusion ring is indicated by 2' and the ribs or vanes by 3', forming channels α' diverging from the medial line α' . 5 Features shown but not alluded to are well understood in the art and need no description in the present connection.

Obviously, the invention is not restricted in its application to elastic fluids such as 10 air or gases, but may be employed in connection with inelastic fluids such as water and the like, as for example in centrifugal pumps for pumping water, oil, or other liquids. It may be stated in passing, that 15 in the operation of the blower the impeller is given a rotation in the direction indicated by the curved arrow in Fig. 1, and by the straight arrow in Fig. 5, that is to say the impeller should rotate in a direction toward 20 the vertices of the converging channels or nozzles α (or toward the vertices of the converging ribs 3), to properly direct the currents as they leave the impeller blades, into and through the channels of the diffusion 25 member 2.

In the present example, the impeller blades B are secured to angles d fastened to 30 a disk m which is keyed to the shaft S, the edges of the blades being stiffened by angles t ; but any other manner of constructing the impeller and fastening the blades to the impeller shaft may be resorted to, this 35 feature not being important in the present connection.

35 Having described my invention what I claim is:

1. In an apparatus of the character described, a rotary impeller, a collecting scroll for the fluid, and a member interposed between the scroll and impeller for conducting the fluid from the impeller to the sides of the scroll chamber. 40

2. In an apparatus of the character described, a rotary impeller, a casing therefor provided with induction and eduction means, a collecting scroll encompassing the periphery of the impeller, and a member interposed between the impeller periphery and the scroll for conducting the fluid 45 from the impeller to the sides of the scroll chamber.

3. In an apparatus of the character described, a rotary impeller, a collecting scroll disposed adjacent the impeller, a peripherally closed ring-like member interposed between the periphery of the impeller and the scroll, and suitable conduits disposed on said member for conducting the fluid from the impeller to the scroll chamber. 55

60 4. In an apparatus of the character described, a suitable impeller, a collecting scroll, and a laterally diffusing member interposed between the impeller and scroll for discharging the currents into the scroll chamber.

5. In an apparatus of the character described, a suitable rotary impeller, a collecting scroll, and a peripherally closed, laterally diffusing ring interposed between the impeller and scroll for discharging the currents leaving the impeller, into the scroll chamber and thereby converting the velocity energy of said currents into a static pressure head within said chamber. 70

6. In an apparatus of the character described, a rotary impeller, a collecting scroll, and means interposed between the periphery of the impeller and the scroll for circumferentially and laterally diffusing the fluid as it leaves the impeller, and discharging the 75 same into the scroll chamber.

7. In an apparatus of the character described, a rotary impeller, a collecting scroll, and an annular member or ring interposed between the periphery of the impeller and scroll and provided with spiral passageways or conduits for circumferentially and laterally diffusing the fluid as it leaves the 80 impeller and discharging the same into the scroll chamber. 85

8. In an apparatus of the character described, a rotary impeller, a collecting scroll, a ring interposed between the scroll and the periphery of the impeller, suitable conduits on the inner face of the ring disposed at an angle to the plane of rotation of the impeller and terminating respectively at points contiguous to the central rotation plane of the impeller and at the sides of the ring 95 within the scroll chamber, and operating to diffuse the fluid circumferentially and laterally as it leaves the impeller and discharge the same into the scroll chamber. 100

9. In an apparatus of the character described, a rotary impeller, a collecting scroll, a ring interposed between the scroll and the periphery of the impeller, suitable conduits 105 on the ring disposed on each side of a medial line thereof and inclined at a slight angle to said line, the outer ends of the conduits opening into the scroll chamber, whereby the fluid as it leaves the impeller is diffused circumferentially and laterally on opposite sides of said medial line of the ring, and the fluid discharged into the scroll chamber. 110

10. In an apparatus of the character described, a rotary impeller, a collecting scroll, a ring interposed between the scroll and the periphery of the impeller, suitable rib or vane formations on the inner face of the ring disposed on each side of a medial line thereof and inclined at a slight angle to said line, said ribs forming corresponding channels between them, a casing for the impeller, suitable ledges or 115 formations on the casing for engaging the outer portions of the longitudinal edges of the ribs whereby the corresponding portions of the channels are closed peripherally, thereby forming conduits or nozzles, the lat- 120 130

ter opening at their outer ends into the scroll chamber, the inner ends of the channels being disposed in proximity to the center of the periphery of the impeller, whereby 5 the fluid leaving the impeller is diffused circumferentially and laterally and delivered on opposite sides into the scroll chamber.

11. In a centrifugal blower, a suitable casing, an outer collecting scroll, a rotary impeller 10 mounted in the casing within the scroll, and means for laterally diverting the fluid as it leaves the impeller, in circumferential paths disposed on opposite sides of the central plane of rotation of the impeller, and 15 discharging the same into the scroll chamber.

12. In an apparatus of the character described, an annular diffusion member provided with channel formations disposed on each side of a medial circumferential line, 20 said channels being disposed at a slight incline to said line and having discharge ends terminating at the sides of said annular member.

13. In an apparatus of the character described, a diffusion ring provided on its 25 inner surface with series of ribs diverging laterally from common vertices disposed along a medial circumferential line and at a slight angle to said line, the ribs forming 30 corresponding diverging channels having

their terminals respectively at said line and at the sides of the ring.

14. In an apparatus of the character described, a rotary impeller, a collecting scroll, and an annular laterally discharging member 35 interposed between the impeller and the walls of the scroll for converting the kinetic energy of the fluid leaving the impeller into potential energy in the form of static pressure. 40

15. In an apparatus of the character described, a rotary impeller, a collecting scroll, and an annular circumferentially guiding and laterally diffusing member interposed 45 between the impeller and the walls of the scroll for converting the kinetic energy of the fluid leaving the impeller into potential energy in the form of static pressure.

16. In an apparatus of the character described, a suitable impeller, a collecting scroll, and a laterally diffusing member for receiving the fluid as it leaves the impeller and discharging the same into the scroll 50 chamber.

In testimony whereof I affix my signature, 55 in presence of two witnesses.

JOHN E. GREENAWALT.
